UNITED STATES PATENT OFFICE

2,440,085

MACHINE FOR APPLYING CLOSURES
AND SEALING JARSGustave Glocker, Washington, D. C., assignor to
Super-Seal Container Corporation, Washington, D. C.

Application June 5, 1944, Serial No. 538,775

6 Claims. (Cl. 226—80)

1

This invention relates to an apparatus for applying closures and sealing jars. More specifically, the object of the invention is to provide for the more accurate positioning of closures with respect to the mouth of the container to insure accurate engagement and a more perfect seal.

Mechanisms for elevating a jar into engagement with a closure to provide sealing are known. Such mechanisms have been used in the application of closures of hard material such as metal or glass and in the application of closures of soft material such as cardboard fibre and the like.

In the case of closures made of soft material, the accurate centering above the mouth of the container immediately prior to sealing engagement is not essential since the closure material will deform sufficiently to adjust itself to minor misalignment. Also in the case of closures of soft material such as cardboard, it is not necessary to provide a hermetic seal and accurate positioning is not essential. Thus in those machines wherein soft closures are mechanically pushed into a closure-applying station, stops and catches for preventing additional entering movement of a closure or preventing withdrawal are adequate even though inaccurately located and not available for adjustment.

In the case of closures constructed of hard material where a hermetic seal is required, the closure must be more accurately positioned above the mouth of the jar immediately prior to the sealing engagement. This has been accomplished as disclosed in my Patent No. 2,335,052, granted November 23, 1943, by positioning a stack of closures in vertical alignment with the axis of the mouth of the enclosure. The lowermost closure is thus always in a position to receive the mouth of the container and no moving part of the mechanism need come into contact with the cap to disturb this relationship. However, where the construction of the mechanism is such that the closure magazine is desirably located remotely, it becomes necessary to push the closure into the proper position to receive the mouth of the container and accurate centering is then more difficult. Close machining tolerances of the pushing mechanism are necessary to reduce play and produce consistent placement. A tendency is also noted for the pushing device to draw the closure with it on the return stroke. Such retraction is generally limited to a small fraction of an inch; nevertheless, this is sufficient to cause erratic and inaccurate positioning unless the mechanism is designed to prevent this effect.

One of the objects of my invention is to pro-

2

vide apparatus of the type indicated which will insure accurate positioning of a closure in spite of the tendency of a pushing device to retract the closure on the return stroke.

Another object of my invention is to provide apparatus which will produce accurate positioning of a closure even though the highest grade of machining tolerances are not used.

Another object of my invention is to prevent over-travel of the closure beyond the optimum condition which may be caused by the momentum imparted to the closure by the mechanism used to push the closure into position.

Another important object of my invention is to provide a mechanism that is effective to apply a yielding pressure to a closure applied to the jar and to this end a spring biased head plate is located over the elevating mechanism so that the jar-lifting elevator may carry the jar with the closure applied thereto into contact with the head plate to apply an initial sealing pressure to the closure.

In accordance with the present invention accurate and consistent positioning of the closure is accomplished by providing a latch or pawl within the spring loaded head plate which engages an annular rim on the closure after it has been transported to the desired position in the closure-supplying station, thus preventing any displacement of the closure which may be caused by the reverse movement of the closure-transferring mechanism.

The spring biased head plate against which the closure is pressed also contacts the closure being transported from the closure magazine to the closure-applying station with sufficient yielding contact to prevent overtravel of the closure and to provide a mechanical load on the pushing mechanism to reduce the effect of looseness or play in the associated linkage.

Various other objects and advantages will be apparent from the following description.

The preferred embodiment of my invention is illustrated in the accompanying drawings wherein similar characters of reference designate corresponding parts and wherein:

Figure 1 is an isometric external view of the closure-applying machine;

Figure 2 is a transverse cross sectional view 50 of the machine shown in Figure 1 taken through the closure-applying station;

Figure 3 is a longitudinal cross sectional view taken on line 3—3 of Figure 2; and

Figure 4 is a transverse cross sectional view taken on line 4—4 of Figure 3.

The machine illustrated in the drawings has a supporting frame consisting of two base members 1 and 2 between which are fixed a horizontal frame 3 which supports a table 4 over which jars to be sealed are moved in a step by step manner by means of an intermittently operated conveyor 5. The conveyor incorporates cross pieces 6 for engaging the jars and moving the same along the surface of the table. The conveyor is given an intermittent movement by intermittently driven sprocket wheels, not shown, which are powered by the same power source, not shown, which drives shaft 7.

The table is provided with a transverse elevator section 8 located under a steam chamber 14. The elevator is urged above the level of the table by spring biased means not shown which acts upon lever 9 and pivot 10. The elevator is, however, kept in its normally depressed position in the plane of table 4 by means of a cam 11 which is fixed to and rotates with shaft 7. The cam 11 lies in contact with a cam roller 12 fastened to the elevator by the pinion 13.

Rotation of shaft 7 thus causes intermittent operation of the elevator 8. The upward movement of the elevator brings the jars into the steam chamber 14 to which steam is conducted by means of pipes 15 prior to the engagement of the mouth of the jar and the closure. The steam chambers are provided with reduced tapered throat portions 16. This throat serves to accurately and uniformly position a jar at the closure-applying station.

Magazines 17a and 17b are provided for the storage of closures which are kept therein in a stacked condition. The lowermost closure rests on base plate 18.

The mechanism which is used to transport the lowermost closure from the magazine to the closure-applying station at throat 16 of the steam chamber 14 operates as follows: Rotation of shaft 7 causes rotation of cam 17 which is rigidly fixed thereto. A cam follower roller 18a biased into contact with cam 17 by means of spring 19 causes rotation of an arm 20 about a pinion 21. This causes reciprocating movement of an arm 22 which, transmitted through a crank 23, a shaft 24, a crank 25, and an arm 26 causes reciprocation of a pushing member 27. This pushing member slides on plate 18 and is kept in engagement with plate 18 by hold down plates 28. The hold down plates are slotted to provide clearance for a bracket 29.

The front or closure-engaging edge of the pushing member 27 is provided with a cut-out concave portion 27a shaped to fit the circular outside edge of a closure. Reciprocating movement of the pushing member translates the lowermost closures to a position above throats 16. The notch need not be circular in section; it may be of any shape so long as the concavity formed thereby enables proper centering of the closure transversely with respect to the pushing member.

Above each throat 16 is located a head plate 30 slidably mounted on pins 31 and downwardly biased by means of springs 32. In apertures provided in the head plates 30 are provided pawls 33 pivoted to the pressure plate by pins 34. Figure 3 shows the pawl in its normal gravity biased condition prevented from further travel by the stop 35. Mounting the pawl resiliently as shown enables the pawl to move out of the way upon interference of an entering closure with a portion of the pawl such as the heel portion 35a. By proper adjustment of the lengths of the arms of

the above-described linkage readily apparent to a mechanic, the length of the stroke of the closure pushing member can be adjusted so that a closure is transported from the bottom of the magazine to a centered position with respect to the mouth of a jar.

The length of the pawl between the pinion 34 to the closure-engaging corner 36 is such that the corner 36 engages an annular rim or similar projection on the closure when the closure moves to a centered position with respect to the mouth of a jar. It will be seen that the pawl is readily accessible for adjusting this distance. The pawl is also readily accessible to modify as required to accommodate closures having a rim or other projection of different radius from the center of the closure than shown.

The height of the space under the spring pressed head plates 30 is not substantially more than the thickness of a closure. Thus, the springs 32 are put under slight compression during the passage of a closure and until the jar is withdrawn. This compression which is the same for each closure provides uniform sealing pressure on each jar. The springs 32 are of the same size and are symmetrically disposed about the center line of the jar. This results in uniform pressure around the periphery of the closure and thus uniform pressure at the sealing edge. The pressure exerted by the pressure plate also causes a frictional resistance to the movement of a closure. This resistance prevents the closure from overtravel, in other words, from being carried beyond the desired position by virtue of its momentum. This resistance also increases the accuracy of positioning brought about by the pushing member 27 by putting a mechanical load on the system and thus reducing the effect of play.

The mechanism is constructed and adjusted so that the intermittent movement of the conveyor 5, of the cam 11 and of the cam 17 and their associated parts produces the sequence of operations as hereinbelow described.

With jars on the conveyor 5 intermittent motion of the conveyor will place two jars on the elevator 8. Simultaneous motion of the shaft 7 and cam 17 acting through the linkage consisting of arms 20, 22, 23, 25, and 26 will cause a closure to be pushed by the pushing member 27 from the bottom of each of the closure magazines, along plate 18 and under pressure plates 30 compressing springs 32. Pawl 33 will be tilted until passage of corner 36 of the pawl over the annular shoulder on the closure.

At the same time that the shaft 7 rotates cam 17, it also rotates cam 11 allowing the elevator to rise with two jars under the influence of upwardly directed spring bias bringing the jars into the steam chamber 14 and causing the mouths of the jars to pass through the restricted openings 16 into engagement with the closures. Additional upward movement of the elevators causes additional compression of the springs 32 and a resultant sealing force bearing evenly around the periphery of the closures.

Steam is admitted to the steam chamber 14 before the jar and closure are brought into contact with each other, and as a result of its presence during the closure-applying operation, live steam is trapped in the head space of the jar. Subsequent condensation of the trapped steam produces a rarefied atmosphere within the jar and a consequent sealing of the jar under the influence of atmospheric pressure, in known

manner. Further movement of shaft 7 causes lowering of the elevator 8 and retraction of the pushing member 27. After the elevator has been lowered to the level of the table 14, the conveyor moves two additional jars into position and the cycle is repeated.

While the practice of the invention has been described with regard to a particular machine which embodies certain novel features, it is to be understood that the machine may be modified in numerous ways without departing from the spirit of the invention and that in fact other machines may be used in accordance with the teaching herein so long as such machines make provision for the use of a pawl to accurately position closures with respect to the mouth of a jar.

I claim:

1. In a closure-applying machine of the class wherein a jar is transported to a closure-applying station and moved axially into engagement with a closure, reciprocating transporting means for laterally sliding a closure from a position of storage to said closure-applying station, a head plate resiliently bearing upon said closure during said sliding movement, a pawl mounted in said head plate at said closure-applying station to engage a closure to retain it in a position axially centered with respect to said jar and to prevent its withdrawal by said reciprocating transporting means on the return stroke.

2. In a closure-applying machine of the class wherein a jar is transported to a closure-applying station and moved axially into engagement with a closure, a closure storage station, reciprocating closure transporting means for laterally sliding a closure from said storage station to said closure-applying station, a downwardly biased head plate for providing lateral pressure on said closure during said sliding movement, a pawl positioned at said closure-applying station, said pawl allowing said closure to enter said closure-applying station but retaining it in an axially centered position with respect to said jar.

3. In a closure-applying machine of the class wherein a jar is transported to a closure-applying station and moved into engagement with a closure, a closure storage station, reciprocating closure transporting means for laterally sliding a closure from said storage station to said closure-applying station, a downwardly biased head plate for providing lateral pressure on said closure during said sliding movement, a pawl positioned at said closure-applying station allowing said closure to enter said closure-applying station but retaining it in an axially centered position with respect to said jar, said pawl be-

ing resiliently mounted to minimize interference of said pawl with said closure upon sliding of said closure into said closure-applying station.

4. In a machine for applying closures to jars and the like, a jar-receiving throat, pushing means to push closures into a position above said jar-receiving throat, a jar elevator located below said jar-receiving throat for moving jars in an axial direction, a downwardly biased head plate at the upper end of said jar-receiving throat, said headplate being effective both to provide lateral pressure upon said closures while they are pushed into position above said jar-receiving throat and to serve as a pressure-applying abutment for closures upon continued axial movement of jars on said elevator.

5. In a machine for applying closures to jars and the like, a jar elevator for moving jars in an axial direction, a jar-receiving throat above said elevator, reciprocating closure-transporting means for laterally sliding a closure into a position above said jar-receiving throat, said transporting means being operatively timed with said jar elevator, a headplate mounted at the upper end of said jar-receiving throat, said headplate being yieldingly positioned both to provide lateral pressure upon said closure during transportation into position above said jar-receiving throat and to serve as a pressure-applying abutment for a closure upon continued axial movement of a jar on said elevator, and a pawl carried by said headplate for engaging and positioning a closure above said jar-receiving throat.

6. In a closure-applying machine of the class wherein a jar is transported to a closure-applying station and moved axially into engagement with a closure, a closure storage station, reciprocating closure transporting means for laterally sliding a closure from said storage station to said closure-applying station, a head plate overlying the closure-applying station, and a pawl pivoted to said head plate at said closure-applying station, said pawl allowing said closure to enter said closure-applying station, but retaining it in an axially centered position with respect to said jar upon withdrawal of said reciprocating closure transporting means.
